Baldwin & Wright

UNITED STATES PATENT OFFICE.

WILLIAM HOWARD LIVENS, OF HAMPSTEAD, LONDON, ENGLAND.

MORTAR.

1,303,079.

Specification of Letters Patent.

Patented May 6, 1919.

Application filed September 4, 1918. Serial No. 252,542.

To all whom it may concern:

Be it known that I, WILLIAM HOWARD LIVENS, a subject of the King of Great Britain, residing at Hampstead, London, England, have invented a new and useful Improvement in Mortars, of which the following is a specification.

This invention relates to a mortar and especially to an improved charge box which 10 enables increased charges to be thrown and longer ranges to be obtained, particularly when the mortars or projectors used are unbored and the projectiles unturned. The apparatus is more particularly designed for 15 the projection of large quantities of lethal gas, and the consequent production of high concentrations by means of electrically fired simultaneous salvos.

In the accompanying drawings, which 20 illustrate the present invention, Figure 1 is a part sectional elevation of the improved charge box and bomb in position within the mortar, Fig. 2 is an enlarged sectional view of the charge box showing the method of 25 housing the electric conductors within the hollow end of the gas check, and Fig. 3 is an end view of a portion of the charge box showing the partitions therein.

a is a steel gas-check combined with a tin 30 box *b* forming the container or charge box for the propellant charge, which may be of flake cordite or other suitable propellant.

When loaded in the mortar the electric leads *c* connected to the box pass along the 35 barrel *d* from the muzzle end in the relatively large clearance space between the bore and the bomb and through holes as *e* in the flange *f* of the steel gas-check *a* into one of the bags *g* of cordite or powder 40 forming the propellant charge where they terminate in an electrically fired ignition fuse *h* which may be surrounded by any known ignition charge. For transport the leads are coiled conveniently into the space 45 formed in the cup-shaped gas-check receiving the end of the bomb, and are covered by a temporary lid *i*. A cover *j* closes the rear end of the charge box.

On firing, the flange of the steel gas-check 50 forming the top of the charge box is expanded by the pressure of the gases and

thus prevents the escape of these gases through the relatively large clearance space between the mortar and the bomb; in this manner it is possible to obtain longer ranges 55 with the light short mortars employed.

The bomb or drum *k*, which forms the subject of a concurrent application, is of steel tube closed in at the ends; these are welded on to a central tube which forms a 60 strong stay; for gas purposes this tube is provided with a diaphragm *n* placed near the base, dividing it therefore into two chambers.

The short chamber at the base end is fitted 65 with a screw plug and has cross holes *m*, by which the liquid gas is introduced into the bomb; the longer end is packed with the bursting charge and takes the gaine *o* and the fuse *p*.

It is obvious that the gas-check and charge box (which allow bombs to be used with more than 3% clearance, *i. e.*, difference in diameter between the bomb and the mortar tube) can be used with bombs of other 75 construction for still larger ranges and higher pressures than those for which the foregoing as described is designed.

What I claim is:

1. In a mortar, the combination with a 80 charge box, of a flanged gas-check attached thereto, and an electric lead within the mortar and running from the muzzle to the charge box.

2. In an unbored mortar, the combination 85 with a charge box, of a flanged gas-check attached thereto and fitting loosely within the mortar, and an electric lead within the mortar and running from the muzzle to the charge box.

3. In an unbored mortar, the combination with a charge box, of a flanged gas-check attached thereto and fitting loosely within the mortar, an electric lead within the mortar and running from the muzzle 95 to the charge box, and an unturned projectile fitting loosely in the mortar.

4. In a mortar, the combination with a charge box having a cup-shaped flanged gas-check attached thereto, of an electric 100 lead within the mortar and running from the muzzle to the charge box, and a projec-

2
tile loosely fitting the mortar and having its base shaped to fit into the cup of the gas-check.

5. A charge box having a flanged cup-shaped gas-check attached thereto and an electric lead connected to a fuse in the charge box.

6. A charge box having a flanged cup-

shaped gas-check attached thereto, an electric lead connected to a fuse in the charge ¹⁰ box and a lid fitting the flange of the gas-check.

In testimony that I claim the foregoing as my invention I have signed my name this 31st day of July, 1918.

WILLIAM HOWARD LIVENS.
